CLAIM

The ornamental design for a hydraulic cylinder bottom end cap as shown and described.

DESCRIPTION

FIG. 1 is an upper left perspective view of the hydraulic cylinder bottom end cap showing my new design;

FIG. 2 is a lower right perspective view thereof;

FIG. 3 is a front elevational view thereof with cross sectional indication line 9-9;

FIG. 4 is a right side elevational view thereof;

FIG. 5 is a duplicate of FIG. 3, which is a front elevational view thereof, without line 9-9 being present;

FIG. 6 is a left side elevational view thereof;

FIG. 7 is a top plan view thereof;

FIG. 8 is a bottom plan view thereof; and,

FIG. 9 is cross sectional view taken along line 9-9 of FIG. 3.

1 Claim, 8 Drawing Sheets
